(57) **CLAIM**

The ornamental design for a set of screed plates, as shown and described.

DESCRIPTION

FIG. 1 is a rear top perspective view of a set of screed plates, containing a left extender screed plate, a main screed plate, and a right extender screed plate, showing our new design; FIG. 2 is an enlarged rear top perspective view of the screed plate bar of FIG. 1;

FIG. 3 is an enlarged top view thereof;

FIG. 4 is an enlarged bottom view thereof;

FIG. 5 is an enlarged front view thereof;

FIG. 6 is an enlarged rear view thereof;

FIG. 7 is an enlarged right side view thereof;

FIG. 8 is an enlarged left side view thereof;

FIG. 9 is an enlarged rear top perspective view of the left extender screed plate of FIG. 1, the right extender screed plate being a mirror image thereof;

FIG. 10 is an enlarged top view of the left extender screed plate, the right extender screed plate being a mirror image thereof;

FIG. 11 is an enlarged bottom view of the left extender screed plate, the right extender screed plate being a mirror image thereof;

FIG. 12 is an enlarged rear view of the left extender screed plate, the right extender screed plate being a mirror image thereof;

FIG. 13 is an enlarged front view of the left extender screed plate, the right extender screed plate being a mirror image thereof;

FIG. 14 is an enlarged left side view of the left extender screed plate, the right extender screed plate being a mirror image thereof; and,

FIG. 15 is an enlarged right side view of the left extender screed plate, the right extender screed plate being a mirror image thereof.

The portions depicted in broken lines of even length are environment and form no part of the claimed design.

1 Claim, 9 Drawing Sheets
